UNITED STATES PATENT OFFICE.

JOHN R. VANDER PUTTEN, OF NEW PHILADELPHIA, OHIO, ASSIGNOR TO THE WISE-MCLUNG MANUFACTURING COMPANY, OF NEW PHILADELPHIA, OHIO, A CORPORATION OF OHIO.

SWITCH-ACTUATING DEVICE FOR ELECTRIC CARPET-SWEEPERS.

1,391,501.

Specification of Letters Patent. Patented Sept. 20, 1921.

Application filed September 14, 1917. Serial No. 191,486.

To all whom it may concern:

Be it known that I, JOHN R. VANDER PUTTEN, a citizen of the United States, residing at New Philadelphia, in the county 5 of Tuscarawas and State of Ohio, have invented a new and useful Switch-Actuating Device for Electric Carpet-Sweepers, of which the following is a specification.

My invention relates to improvements in 10 switch actuating devices for carpet sweepers and has more especial reference to a device of this character arranged to be operated by the foot.

The object of this invention is to provide 15 a device of this character having an operating pedal located near the floor and arranged to be operated by the foot.

A further object is the provision of an 20 electric carpet sweeper with a switch actuating device located adjacent the floor and and arranged to be operated with the foot, the foot pedal being so located with reference to the floor that it may be easily operated without raising the foot entirely off 25 of the floor.

With these objects in view the invention 30 consists in the novel construction and arrangement of parts, hereinafter described, illustrated in the accompanying drawings, and particularly pointed out in the appended claims, it being understood that various changes in the form, proportions, size 35 and minor details of construction may be made within the scope of the appended claims, without departing from the spirit or sacrificing any of the advantages of the invention.

In the drawings:

Figure 1 is a side elevation of a carpet 40 sweeper provided with my improved switch actuating device.

Fig. 2 is a section on line 2—2, Fig. 1.

Fig. 3 is a detail perspective view of the operating lever.

Similar numerals of reference indicate 45 corresponding parts throughout the several figures of the drawings.

Referring more especially to the construction illustrated in the accompanying drawings, the numeral 1 indicates the nozzle, the 50 numeral 2 the fan casing and the numeral 3 the motor casing of an electric carpet sweeper of any usual and approved construction which is mounted upon rollers 4

and arranged to be moved over the carpet 55 or other surface to be cleaned by means of a handle 5.

The motor casing 3 is provided with a switch indicated generally by the numeral 6 which is of the usual construction and is 60 provided with a chain 7 arranged to be pulled outward to either open or close the switch, means being provided for bringing the chain back into the normal position after each operation thereof. It is, of 65 course, understood that this form of a switch is common in devices of this kind.

The present invention has to do with means for operating this chain to open or close the switch without the necessity of the 70 operator stooping over to grasp the chain and for this purpose the foot lever 8 is pivoted intermediate its extremities to the lugs 9 formed upon the casing; the upper extremity of said lever being twisted at right 75 angles as indicated at 10 and provided with a bifurcated portion 11 which receives the free extremity of the chain 7, the usual button 12 upon said chain holding the same in position as shown in the drawings. The 80 lower extremity of the lever 8 is provided with the outwardly disposed treadle portion 13 arranged to be depressed by the operator in order to draw the chain 7 outwardly from the switch to either open or close said switch 85 as desired. It will, of course, be understood that the treadle portion 13 may, if desired, be turned in the opposite direction from that shown in the drawings, in which case the toe of the operator would be placed beneath the treadle to raise the same when it is desired to open or close the switch. With 90 either of these constructions it will be seen that a very simple and efficient means is provided for operating the switch 6 to start 95 or stop the motor without the necessity of the operator stooping over to operate the switch and it will be seen that the treadle 13 is so located with reference to the floor that it is not necessary for the operator to 100 raise the foot entirely off of the floor to operate the switch, and the operator is thus not thrown off of his or her balance when operating this switch with the foot.

I claim:

1. In an electric carpet sweeper of the character described, a switch controlling the motor of said sweeper, a chain operatively

connected to said switch to open or close the switch and a foot lever pivotally mounted upon the casing of the sweeper and comprising a substantially vertical long arm 5 provided with an upper bifurcated end to receive the end of the chain and a substantially horizontal short foot treadle located in proximity to the floor.

2. In combination with a vacuum cleaner 10 having an electric motor for operating it and a casing for the motor, of a switch for controlling the motor circuit mounted on the motor casing, and an operating lever for the switch pivoted adjacent the switch 15 and projecting to the side of the motor casing whereby it is adapted to be operated by the foot of the operator.

3. In combination with a vacuum cleaner having an electric motor for operating it 20 and a casing for the motor, of a switch for

controlling the motor circuit mounted on the motor casing, and an operating lever for the switch pivoted adjacent the switch and projecting beyond the motor casing whereby it is adapted to be operated by the 25 foot of the operator.

4. In combination with a vacuum cleaner having an electric motor for operating it and a casing for the motor, of a switch for controlling the motor circuit mounted on 30 the motor casing directly behind the motor, and an operating lever for the switch pivoted adjacent the switch and projecting to the bottom of the motor casing whereby it is adapted to be operated by the foot of 35 the operator.

In testimony that I claim the above I have hereunto subscribed my name.

JOHN R. VANDER PUTTEN.
